FURNACE DOOR OPERATING MECHANISM

Edward A. Hanff, Pittsburgh, Pa., assignor to
 Swindell-Dressler Corporation, Pittsburgh, Pa.,
 a corporation of Pennsylvania

Application April 22, 1947, Serial No. 743,083

12 Claims. (Cl. 110—176)

1 The general object of the present invention is to provide an improved door or closure operating mechanism of a type adapted for use in moving a furnace door or analogous closure into and out of the position in which it closes an opening in the vertical wall of a furnace or processing chamber, and for use in maintaining a relatively large sealing pressure between the closure and chamber structure, when the closure is in its closed position. A door or closure of the type referred to usually comprises a metal framework and masonry, and is of such size that the door ordinarily weighs several thousand pounds. The maintenance of a gas tight joint between the chamber structure and the closure in the closed condition of the latter, requires a suitable sealing pressure force, which in some cases may be substantially greater than the weight of the door.

The invention relates particularly to closure operating mechanism for a furnace or processing chamber closure which in each opening and each closing operation is moved vertically between a lower level at which the closure closes the doorway and a higher level at which all or a portion of the closure is above the doorway. A primary object of the present invention is to provide improved means for moving the closure horizontally toward and away from the doorway in a final closing operation and in an initial stage of the opening operation, respectively, so as to provide suitable clearance between the chamber structure and the closure while the latter is being moved vertically between positions in which it does and does not entirely close the doorway.

A specific object of the invention, of primary practical importance is to provide closure operating mechanism comprising hoisting and counter-weight devices connected to the closure by lever and link arrangements, so that the counter-weight action will reduce the hoisting device power required to give the closure its vertical movements, and in which the counter-weight action is utilized in giving the closure its horizontal guided closing movements, and to provide the closure sealing effect needed, and in which the hoisting device gives the closure its horizontal opening movements, and in which the counter-weight and hoisting device cooperate in giving the closure its vertical movements.

The present invention may be used with especial advantage in operating the doors or closure of furnace and processing chambers of various types including relatively heavy closures, and in which a tight joint between the chamber structure and closure, when it is in its closed position,

2 is needed to prevent the escape of heat or to maintain a desired atmosphere within the furnace or processing chamber. In such cases, gaskets or resilient sealing strips may be employed to insure gas tight joints, and mechanical clearance between the closure and chamber structure during the vertical movements of the closure is then required to avoid injury to the gaskets and sealing strips, and such clearance is generally desirable to avoid wear and scraping of closures and chamber structures.

Heretofore, numerous closure operating mechanisms have been proposed for furnaces and processing chambers of the type with which the present invention may be used with advantage, but all such prior arrangements of which I have knowledge, are open to one or more objections which it is the object of the present invention to avoid.

The various features of novelty which characterize my invention are pointed out with particularity in the claims annexed to and forming a part of this specification. For a better understanding of the invention, however, its advantages, and specific objects attained with its use, reference should be had to the accompanying drawings and descriptive matter in which I have illustrated and described a preferred embodiment of the invention.

Of the drawings:

Fig. 1 is a plan view of apparatus shown in Fig. 2;

Fig. 2 is a front elevation, with parts broken away, of a portion of a furnace including an embodiment of the invention;

Fig. 3 is a side elevation with parts broken away and in section, of apparatus shown in front elevation in Fig. 2;

Figs. 4 and 5 are sectional elevations taken similarly to Fig. 3, but showing parts in different relative positions;

Fig. 6 is a plan section taken on the line 6—6 of Fig. 3; and

Figs. 7 and 8 are diagrammatic elevations showing a door in different positions and indicating the relative values of door operating forces in different door positions.

In the drawings, I have illustrated an embodiment of the present invention included in a metal treating furnace A comprising a furnace chamber B with a door opening C formed in a vertical masonry wall of the chamber B. The door opening is normally closed by a furnace door which is of conventional type for use in furnaces of the general type shown and comprises non-metallic refractory and heat insulating material mounted

in a metallic frame structure. In the closed position of the door, its marginal portion of its inner face fits snugly against the door jamb and lintel portions of the outer wall of the furnace at the margin of the door opening C, and the weight of the door is supported by stationary horizontal track members 1 perpendicular to and extending away from the portion of the furnace wall below the doorway C.

The initial door opening and the final door closing movements are horizontal movements in the direction of the length of the track members 1. To facilitate those movements, the door is advantageously provided with rollers 2 which are journalled in brackets 3 attached to the door and rest on the track members 1. In the normal closed position of the door shown in Figs. 1, 2 and 3, the weight of the door is supported by the track members 1 through the rollers 2, and the door is pressed against the portion of the furnace wall surrounding the door opening C with a predetermined sealing pressure.

The sealing pressure is applied through bell crank levers 4 mounted on pivots 5 anchored in the door structure and extending horizontally away from the vertical side edges of the door. As shown, the door is provided at each side with an upper lever 4 and a lower lever 4. Each lever 4 has a relatively short arm and a relatively long arm. The short arm of each bell-crank lever 4 carries a horizontal crank pin or cam portion 6 which extends into a stationary vertical guide-way formed by the trough of a channel bar 7. As shown, each crank pin 6 supports an anti-friction sleeve or roller which directly engages the guide bar 7. There are two channel bars 7, one at each side of the door and each rigidly secured to the furnace structure. As will be apparent, turning movements of the levers 4 which are counter-clockwise as seen in Figs. 3 and 4, will move the door from its closed position shown in Fig. 3, into its partially open position shown in Fig. 4, since the lever fulcrums are formed by the stationary channel bars 7. In consequence, any such counter-clockwise turning movement given to a lever 4 results in a horizontal movement of the lever pivot 5 which is anchored in the door, in the direction to move the door away from the furnace. Conversely, when the door is in the partially open position, shown in Fig. 4, clockwise turning movements of the levers 4, as seen in Figs. 3 and 4, move the door toward its closed position.

The door operating mechanism comprises two door operating members 8, one at each side of the door and each pivotally connected to the outer end of the long arm of each of the two levers 4 at the corresponding side of the door. As shown, each door operating member 8 is in the form of a vertically disposed rod or bar with four collars or circumferentially extending flanges 9. One of the four collars carried by each member 8 is immediately above, and another is immediately below the outer end of the long arm of the upper lever 4 connected to the bar, and one of the other two collars is immediately above and the other is immediately below the outer end of the long arm of the lower lever 4 at the same side of the door. The long arm of each lever 4 is formed with a passage 4' loosely receiving the bar-like body of the corresponding member 8, as is shown in Fig. 6. Each door operating member 8 has its upper end pivotally connected to the arm 10a of a lever 10 pivotally connected to the door by a horizontal pivot pin

11 mounted in a bracket 12 secured to the upper end portion of the door D. Each lever 10 has a second arm 10b longer than its arm 10a and at the opposite side of the lever pivot 11.

5 A counter-weight 13 at each side of the door is connected to the shorter arm 10a of the lever 10 at that side of the door by a flexible element 14 which ordinarily is a wire rope. Each rope 14 runs over a corresponding sheave 15 which is journalled to turn about the axis of a horizontal pivot shaft 15' supported in a bracket 16, mounted on an upper portion of the furnace structure at the corresponding side of the doorway C. Each rope 14 is connected to the corresponding lever 10 between the pivotal connection of the latter to the corresponding member 8 and the lever pivot 11. To move the door from its partially open position, shown in Fig. 4, into its closed position, shown in Fig. 3, each lever 10 is turned clockwise about its pivot 11 as seen in Figs. 3 and 4, by the turning force then transmitted to the lever 10 through the rope 14 by the corresponding counter-weight 13. After the door reaches its fully closed position, the force which the counter-weight 13 transmits builds up a sealing pressure which reacts through the corresponding levers 4 and member 8 to neutralize the torque to which the corresponding lever 10 is subjected by the counter-weight 13 connected thereto.

20 30 35 40 45 50 55 60 65 70 75 The longer arm 10b of each lever 10 is connected to the lower end of a wire rope 17 or other flexible element which has an upper end portion wound around and secured to a corresponding hoisting drum 18. The two hoisting drums connected to the levers 10 at the opposite sides of the door, are mounted on a horizontal shaft 19 journalled in brackets 20 supported by the upper portion of the furnace structure. A worm gear 21 attached to one end of the shaft 19 is operatively engaged by a worm 22 adapted to be rotated by the shaft 23 of a door operating motor 24.

In the closed position of the doors, the hoisting ropes 17 are not under tension, and the counter-weights 13 operate through the levers 10, operating members 8, and levers 4 to establish and maintain a sealing pressure between the furnace structure and the door. When the door D is to be opened, the motor 24 is operated to rotate the shaft 19 in the direction to put the hoisting ropes 17 under tension and apply lifting forces to the longer arms 10b of the levers 10. Since the combined weight of the two counter-weights 13 is something less than the weight of the door D, the first effect of thus putting the ropes 17 under tension is to tilt the levers 10 out of the positions which they occupy when the door is closed as shown in Fig. 3, and into the positions occupied when the door is displaced from its closed position as shown in Fig. 4. As each lever 10, shown in Figs. 3 and 4, is tilted counter-clockwise from the position shown in Fig. 3 to the position shown in Fig. 4, the corresponding operating member 8 is lowered and each lever 4 is turned counter-clockwise and operated as a lever of the second class to turn about its crank pin portion 6 as a fulcrum, and thereby apply a horizontal opening force to the door D through its pivot 5.

The counter-clockwise turning movement of the levers 10 and 4, as seen in Figs. 3 and 4, continues until the levers 4 engage steps 25 in the form of horizontal projections from the corresponding side edge of the door. As the rotation of the hoisting drums 18 continues after moving the levers 10 and 4 into their positions shown

in Fig. 4, the tension of the flexible suspension element 17 increases until the aggregate lifting force exerted by the ropes 14 and ropes 17 slightly exceeds the weight of the door. Thereupon the door begins to move upward to, and then through its intermediate position shown in Fig. 5, into its wholly open position in which the lower edge of the door may be at or near the top of the doorway C. When thereafter, the motor 24 is operated to lower the door D, no change in the angular positions of the levers 4 and 10 occur until the rollers 2 engage the trackways 1 and the tension of the ropes 17 diminishes as the weight of the door is transmitted to the trackways. As the tension of the ropes 17 diminishes, the counter-weights 13 turn the levers 10, and thereby the levers 4 clockwise and thus move the door into reengagement with the furnace wall and reestablish the furnace sealing pressure. With the door operating mechanism shown in the drawings, the counter-weight action thus directly reduces the load on the hoisting motor 24, and operates through the levers 4 to give the door its horizontal closing movement and to establish and maintain the desired sealing pressure when the door is closed. The action of the hoisting mechanism not only effects and regulates the vertical movements and the horizontal opening movement of the door, but also holds the levers 4 in firm engagement with the door carried stops 25, when the door is suspended, and thus holds the door against horizontal or swaying movement.

A ready understanding of the various operating characteristics of the door opening mechanism shown in Figs. 1 to 6, may be facilitated by reference to the schematic Figures 7 and 8. In those figures the door is shown in the same closed and partially opened position in which it is respectively shown in Figs. 3 and 5. In Figs. 7 and 8, the entire counter-weight action may be, and as shown is, due to a single counter-weight 13a connected through a single rope or analogous flexible suspension element 14a to the arm 10a of a single lever 10A. The lever 10A of Figs. 7 and 8 replaces the two levers 10 of the arrangement shown in Figs. 1 to 6. The second arm 10b of the lever 10A is connected to the hoisting mechanism by a single rope or suspension element 17a. In Figs. 7 and 8, the arm 10a of the lever 10A is assumed to be connected to each of the various levers 4. Equal portions of the force impressed on the lever 10A by the counter-weight is transmitted to each of the levers 4. It is further assumed by way of illustration that the door shown in Figs. 7 and 8 weighs 6100 pounds and the single counter-weight 13a weighs 5000 pounds, and that the arm 10b of the lever 10A is about 5 times as long as the arm 10a, and that the bell crank levers 4 are proportioned and arranged so that in the closed position of the door, shown in Fig. 7, the horizontal component of the length of the long arm of each lever 4 is 3 times the length of the vertical component of the short arm of that lever.

On the foregoing assumptions, it will be apparent that when the door is in its closed position as shown in Fig. 7, and the rope 17a is not under tension, the counter-weight subjects the element 14a to a tension of 5000 pounds and thereby subjects the long arm of each of the four levers 4 to an upwardly acting force of 1250 pounds. With the 3 to 1 ratio of the effective lengths of the long and short arms of the levers 4, and on the assumption that those arms are substantially vertical and horizontal, respec-

tively, each lever 4 will then subject the door to a sealing pressure of about 3750 pounds. In consequence, the aggregate door sealing pressure created by the 5000 pound counter-weight is 15,000 pounds. When the door D is suspended as shown in Fig. 8, 5000 of the 6100 pounds door weight is balanced by the counter-weight 13a, and the total lifting force which the hoisting mechanism must supply to hold the door in the position shown in Fig. 8 is only 1100 pounds.

This, with the assumed 5 to 1 arm ratio of the lever 10A, means that a downwardly acting force of about 125 pounds is applied to the long arm of each lever 4 when the closure D is not resting on the tracks 1. With the levers 10A thus held in rigid relation to the door, and with the two levers 4 at each side of the door located at suitable different levels and engaging the walls of the channel bars 7 without unnecessary clearance, the suspended door D is held against undesirable horizontal or swaying movements.

It will be observed that while the levers 4 are out of engagement with stops 25, the aggregate down-thrust of 500 pounds on the long arms of the levers 4 provides an aggregate potential force of 1500 pounds which can be exerted by the short arms of the four levers 4 against the walls of the guideway formed by the channel bars 7, if that force is needed to effect the horizontal movement of the door from its position shown in Fig. 8 to its position corresponding to that shown in Fig. 4. It will be understood that the weights and dimensions above stated are given by way of illustration and example, and not by way of limitation, and that the invention may be used with advantage with door and door operating mechanism weights and dimensions very different from those given above.

With the levers 4 arranged at the levels shown in Fig. 4, the guideway formed by the channel bars 7 must extend from a level adjacent to the bottom of the doorway C to a level appreciably above the top of the doorway, if the levers and guideway are to cooperate in maintaining the door in parallelism with itself in all conditions, as I now consider preferable. However, the invention is not limited to an arrangement in which the levers 4 are arranged to engage guideway portions located at the sides of the doorway C, or to engage a guideway which extends downward below the top of the doorway C.

While in accordance with the provisions of the statutes, I have illustrated and described the best form of embodiment of my invention now known to me, it will be apparent to those skilled in the art that changes may be made in the form of the apparatus disclosed without departing from the spirit of my invention as set forth in the appended claims, and that in some cases certain features of my invention may be used to advantage without a corresponding use of other features.

Having now described my invention, what I claim as new and desire to secure by Letters Patent, is:

1. The combination with structure comprising a vertical wall with an opening therein and a vertical guideway, of a closure movable in a substantially horizontal direction toward and away from said wall between a position in which said closure engages said wall and closes said opening and a second position in which said closure is spaced away from said wall, and movable vertically between said second position and a more elevated third position, lever means

pivotedly connected to said closure, means cooperating with said guideway and actuated by said lever means on pivotal movement in one direction or in the opposite direction to create a force acting between said door and guideway and tending to simultaneously move both the top and the bottom portions of said closure respectively toward or away from said wall, counter balancing means connected to and subjecting said lever means to a lifting force smaller than the weight of the closure and tending to turn said lever means in said one direction, a hoisting device connected to said lever means and subjecting said lever means to a second lifting force varying between a maximum greater, and a minimum less than the difference between the weight of the closure and the first mentioned lifting force and tending to turn said lever means in said opposite direction with a force increasing as said second lifting force increases, said second lifting force acting on said lever means with sufficiently greater leverage than said first lifting force so that said lever is turned in said opposite direction before said second lifting force becomes equal to said difference.

2. The combination with structure comprising a vertical wall with an opening therein and a vertical guideway comprising spaced apart guide surfaces at different distances from said wall of a closure movable toward and away from said wall between a position in which said closure engages said wall and closes said opening and a second position in which said closure is spaced away from said wall, and movable vertically between said second position and a more elevated third position, lever means pivotally connected to said closure, means cooperating with said guideway comprising two bell crank levers at each side of the door and located at different levels, each of said levers being pivotally connected to the door and having one arm connected to said lever means and having its other arm in engagement with said guideway, said levers being actuated by said lever means on pivotal movement in one direction or in the opposite direction to create a force acting between said door and guideway and tending to move said closure respectively toward or away from said wall, counter balancing means connected to and subjecting said lever means to a lifting force smaller than the weight of the closure and tending to turn said lever means in said one direction, a hoisting device connected to said lever means and subjecting said lever means to a second lifting force varying between a maximum greater, and a minimum less than the difference between the weight of the closure and the first mentioned lifting force and tending to turn said lever means in said opposite direction with a force increasing as said second lifting force increases, and second lifting force acting on said lever means with sufficiently greater leverage than said first lifting force so that said lever is turned in said opposite direction before said second lifting force becomes equal to said difference.

3. The combination with a closure for an opening in a vertical wall of operating mechanism for said closure comprising a lever element pivotally connected to said closure, counter balancing means connected to said element and subjecting the latter to a first lifting force smaller than the weight of the closure and to a torque tending to turn said element in one direction, a hoisting mechanism connected to said lever element and operable to subject the latter to a sec-

ond lifting force varying between a value which is smaller, and a value which is larger than the difference between the weight of the closure and said first lifting force, and subjecting said element to a torque tending to turn the lever element in a direction opposite to the first mentioned direction, said counter balancing means and hoisting mechanism being connected to said lever element to operate on the latter with such different leverages that the hoisting mechanism torque increases to equality with the counter balancing means torque as said second lifting force increases from its first mentioned value to a value less than the difference between the weight of the closure and said first lifting force, and closure adjusting means mounted on said closure and actuated by turning movements of said element to exert a horizontal thrust against a fixed object, and thereby move said closure horizontally toward said wall as said lever element is turned in said opposite direction.

4. The combination with a closure for an opening in a vertical wall of operating mechanism for said closure comprising a lever element pivotally connected to said closure, counter balancing means connected to said element and subjecting the latter to a first lifting force smaller than the weight of the closure and to a torque tending to turn said element in one direction, a hoisting mechanism connected to said lever element and operable to subject the latter to a second lifting force varying between a value which is smaller, and a value which is larger than the difference between the weight of the closure and said first lifting force, and subjecting said element to a torque tending to turn the lever element in a direction opposite to the first mentioned direction, said counter balancing means and hoisting mechanism being connected to said lever element to operate on the latter with such different leverages that the hoisting mechanism torque increases to equality with the counter balancing means torque as said second lifting force increases from its first mentioned value to a value less than the difference between the weight of the closure and said first lifting force, and closure adjusting means mounted on said closure and actuated by turning movements of said element to exert horizontal thrusts against a fixed object and thereby move said closure horizontally away from or toward said wall as said lever element is turned in said one direction or in said opposite direction.

5. A combination as specified in claim 3 in which said lever element comprises a pair of levers, one adjacent each side of the closure and each pivotally connected to said closure.

6. A combination as specified in claim 5 in which said adjusting means comprise an upper adjusting lever and a lower adjusting lever at each side of the door and link connected to the lever comprised in said lever means and at the same side of said closure.

7. A combination as specified in claim 3, in which said adjusting means comprises one or more levers, each pivotally connected to said closure and link connected to said lever element.

8. The combination with structure comprising a vertical wall with an opening therein, of a closure movable in a substantially horizontal direction toward and away from said wall between a position in which said closure engages said wall and closes said opening and a second position in which said closure is spaced away from said wall, and movable vertically between said second posi-

tion and a more elevated third position, counter balancing means connected to and subjecting said closure to a first lifting force smaller than the weight of the closure, a hoisting device connected to said closure and subjecting it to a second lifting force variable between a value greater, and a value less than the difference between the weight of the closure and said first lifting force, and means responsive to variations in the relative lifting forces for simultaneously moving the top and bottom portions of said closure toward and away from said wall as said second lifting force decreases below and rises to equality with said difference.

9. The combination with structure comprising a vertical wall with an opening therein and a guideway, of a closure movable toward and away from said wall between a lower position in which said closure engages said wall and closes said opening and a more elevated position in which said opening is not closed, means for moving said door between said positions comprising counterbalancing means subjecting the closure to a lifting force less than the weight of the closure and hoisting means regulable to subject said door to a second lifting force varying between a maximum greater and a minimum less than the difference between the weight of the closure and the first mentioned lifting force, and means mounted on said closure and actuated by said counterbalancing means to cooperate with said structure in pressing said closure against structure with a force substantially greater than the weight of said closure on a predetermined reduction in said second lifting force.

10. The combination with structure comprising a vertical wall with an opening therein, of a closure movable toward and away from said wall between a first position in which said closure engages said wall and closes said opening and a second position in which said closure is spaced away

from said wall, and movable vertically between said second position and a more elevated third position, means for moving said door between its different positions comprising counterbalancing means subjecting the closure to a first lifting force less than the weight of the closure and hoisting means operable to subject said door to a second lifting force varying between a maximum greater, and a minimum less, than the difference between the weight of the closure and said first lifting force, and means movably mounted on said closure and actuated by said counterbalancing means to cooperate with said structure in moving the closure from said second position into said first position on a predetermined reduction in said second lifting force.

11. A combination as specified in claim 9, in which the means movably mounted on said closure cooperates with said structure to hold said closure substantially parallel with itself in moving between its second and first positions.

12. A combination as specified in claim 9, in which said hoisting means actuates said means movably mounted on said closure to cooperate with said structure in moving said closure from its first position to said second position on a predetermined increase in said second lifting force.

EDWARD A. HANFF.
